GARMENT BAG AND THE LIKE

Irving Blechman, New York, N. Y.

Application November 24, 1948, Serial No. 61,777

2 Claims. (Cl. 206—10)

1
The object of the present invention is to provide a garment bag assembly incorporating elements which will more effectively provide adequate protection against moths and other insects over long periods of time. For such purpose there is provided at the top area of the garment bag an insecticide carrier of special form within a frame which has the double function of holding the bag in its rectangular form and transmitting the weight of garments within the bag to an overhead point exterior thereto vaporization of the insecticide, and its direction of emission being controlled, and protection to the walls of the bag and to the clothing being given as against oily or other staining particles from the insecticide.

The invention will be described with reference to the accompanying drawings, in which:

Fig. 1 is a perspective view of a garment bag constituting an embodiment of the invention;

Fig. 2 is a view in elevation partly broken away showing the bag at a narrow side wall thereof;

Fig. 3 is a perspective view of the co-acting hanger frame and insecticide carrier;

Fig. 4 is a view in elevation showing the structure of Fig. 3;

Fig. 5 is an enlarged fragmentary section on the line 5—5, Fig. 3;

Fig. 6 is an enlarged longitudinal section on the line 6—6, Fig. 3;

Fig. 7 is a perspective view showing a modified form of the hanger frame and insecticide carrier;

Fig. 8 is a view in elevation of the structure shown in Fig. 7;

Fig. 9 is an enlarged fragmentary section taken on the line 9—9, Fig. 7;

Fig. 10 is an enlarged fragmentary section taken on the line 10—10, Fig. 7;

Fig. 11 is a fragmentary bottom view, being a corner section of the structure shown in Fig. 7;

Fig. 12 is a vertical section taken on the line 12—12, Fig. 1;

Fig. 13 is a slightly enlarged section taken on the line 13—13, Fig. 3;

Fig. 14 is a vertical section taken on the line 14—14, Fig. 13;

Fig. 15 is a section of Fig. 9, substantially enlarged;

Fig. 16 shows a section or portion of Fig. 6 enlarged.

Referring to the drawings, I have shown at 1 a garment bag in which the body will preferably be made of thin flexible material, such as plastic sheeting, for example. The body of the bag is provided with a side opening which may be tightly closed through the use of a hookless

fastener arrangement indicated at 2. The bottom and the top of the bag are closed. When garments are placed in the bag and the opening closed it will substantially retard vapor emission from the inside under all normal operating conditions, and will be substantially impervious to the entrance of moisture.

Referring to Figures 2 and 3, it will be seen that within the bag is disposed a rectangular wire frame 3 and that extending transversely thereof and carried by the frame 3 through the use of hooked ends 4x is a corrugated cross member 4 adapted to receive coat hangers as indicated in dotted lines at 5x, Fig. 2.

15 As shown in Fig. 6, the corrugated cross member 4 is embraced by a metallic clip 5 and two of these clips 5 are used, as shown in Fig. 2. Each clip receives the head 6x of a hanger 6, the latter passing through apertures in the top of the bag, which apertures may be protected by grommets 7. Thus, when the garment is hung upon a closet rod through the described instrumentalities none of the weight thereof will be directly imposed upon the garment bag itself and the hanger 6 may be rotated to any desired position.

Carried substantially interiorly within the frame 3 is a composite structure constituting the insecticide carrier per se. In the embodiment shown in Figures 5, 6, 14, and 16, the uppermost layer consists of an impervious sheet, which may be plastic, 7, below which is an absorbent layer 8, followed by a pervious sheet 9 which may be of paper and followed by one or more layers of more absorbent material than paper sheet 9, as for example blotting paper. In the drawings two of said sheets, 10, are shown as underlying the sheets 7, 8 and 9.

Preferably the assembly as thus described is marginally bound with the binding as indicated at 11, and after the absorbent sheet 8 has been impregnated with an insecticide or insect repellent fluid. As an alternative, the layer 8 may be a paste of insecticide composition which will not require an absorbent membrane or other neutral absorbent material.

The insecticide carrier per se may be formed with apertures, preferably protected by grommets 12, Fig. 3, through which the hanger 6 may be passed, because a feature of the insecticide carrier is its flexibility. Because of that fact it may be temporarily deformed for application to the hooked ends of the carriers and its movement down to the position of Fig. 3, as a part of the general frame structure.

55 As an effective means for connecting the end

areas of the insecticide carrier to the frame member 3, wire hooks 15 may have their ends projected through grommets 16 and bent over, the loop-hook end of each member 15 embracing member 3, as shown in Fig. 3.

In the structure of Figs. 7, 8, 9, 10, 11 and 15, the hanger frame is the same as that shown in the preceding figures and as described. The insecticide carrier is modified. It consists of an uppermost sheet 17 of impervious material, such as plastic, for example, followed by an insecticide-impregnated absorbent material 18, a paper sheet 19 underlying the layer 18, and a final under sheet of impervious material 20. This sheet 20 may be of plastic and preferably carries at its upper surface a cardboard sheet 21. The sheet 20 is perforated, as at 22, as will be the case with respect to the cardboard sheet 21 when it is used. The size of the perforations will be proportioned in accordance with the degree of volatility of the insecticide composition as will be understood without further explanation. The composite insecticide carrier may be completed by a marginal binding as indicated at 23. This binding may have applied thereto, as at the narrow ends of the insecticide carrier, any suitable means for connecting the carrier to the frame, tapes 24 being shown in the drawings.

While I have in the foregoing referred to the structure shown primarily in Fig. 3, as an insecticide carrier, it will be understood that the structure may be impregnated with a deodorizer or any other desired material which has action and/or volatility, including perfumes which may or may not have added function and that the claims are to be interpreted accordingly.

It will also be noted by reference to Figs. 1 and 2 that means, such as felt washers, may be employed to seal the openings in the bag through which the hangers 6 project. Such sealing means may be employed interiorly of the bag as by the felt washer 71, Fig. 2, on the exterior of the bag, as by the felt washer 70, or at both the inside and exterior of the bag.

Having described my invention, what I claim and desire to secure by Letters Patent, being as follows:

1. A garment bag comprising a body member of light flexible material, said body member having a top and a bottom and being generally rec-

tangular in form, means including a rectangular frame for supporting the body member from an overhead support, said means including at least one hanger secured to the frame and having a shank projected through the top of the bag, and an insecticide carrier underlying the top member of the bag and supported by said frame, said carrier comprising a plurality of layers namely an uppermost layer of impervious flexible plastic material, an intermediate layer carrying insecticide material, an underlying layer adapted to check free emission of the insecticide material, and an outer perforated sheet guarding the layer which checks free emission of the insecticide material said insecticide carrier being flexible and encompassing a major portion of the rectangular frame.

2. A garment bag comprising a body member of light flexible material, said body member having a top and a bottom and being generally rectangular in form, means including a rectangular frame for supporting the body member from an overhead support, said means including at least one hanger secured to the frame and having a shank projected through the top of the bag, and an insecticide carrier underlying the top member of the bag and supported by said frame, said carrier comprising a plurality of layers namely an uppermost layer of impervious material, an intermediate layer carrying insecticide material and an underlying layer, of porous, cellulosic material adapted to control the rate of emission of the insecticide material, the underlying layer consisting of an impervious, perforated, sheet held projected from the intermediate layer which carries the insecticide material, and means connecting said impervious sheet with the remaining elements of said insecticide carrier.
